(57) **CLAIM**

The ornamental design for an elastic fitness band, as shown and described.

DESCRIPTION

FIG. 1 is an isometric view of an elastic fitness band showing my design.

FIG. 2 is a left side elevation view thereof.

FIG. 3 is a right side elevation view thereof.

FIG. 4 is a rear elevation view thereof.

FIG. 5 is a front elevation view thereof.

FIG. 6 is a top plan view thereof; and,

FIG. 7 is a bottom plan view thereof.

The cross-hatching shading in the figures is fragmentarily shown for convenience of illustration, it being understood that the cross-hatching shading is uniformly continued over the surface on which it appears.
